(57) **CLAIM**

The ornamental design for a waist play caller as shown and described.

DESCRIPTION

FIG. 1 is a perspective view of a rectangular waist play caller of a first embodiment, showing my new design;

FIG. 2 is a perspective view of a square waist play caller of a second embodiment;

FIG. 3 is a front plan view of the waist play caller of the first embodiment;

FIG. 4 is a back plan view of the waist play caller of the first embodiment;

FIG. 5 is a first edge view of the waist play caller of the first embodiment;

FIG. 6 is a second edge view of the waist play caller of the first embodiment;

FIG. 7 is a bottom view of the waist play caller of the first embodiment;

FIG. 8 is a top view of the waist play caller of the first embodiment;

FIG. 9 is a back partial view of the waist play caller of the first embodiment when worn;

FIG. 10 is a front partial view of the waist play caller of the first embodiment when worn;

FIG. 11 is an alteration of the waist play caller of the first embodiment whereby broken line sections are removed;

FIG. 12 is a perspective view of the altered rectangular waist play caller of a first embodiment;

FIG. 13 is a perspective view of the altered square waist play caller of the second embodiment;

FIG. 14 is a front plan view of the altered waist play caller of the first embodiment;

FIG. 15 is a back plan view of the altered waist play caller of the first embodiment when worn;

FIG. 16 is a first edge view of the altered waist play caller of the first embodiment when worn;

FIG. 17 is a second edge view of the altered waist play caller of the first embodiment;

FIG. 18 is a bottom view of the altered waist play caller of the first embodiment;

FIG. 19 is a top view of the altered waist play caller of the first embodiment; and

(Continued)

FIG. 20 is a back partial view of the altered waist play caller of the second embodiment when worn; and,
 FIG. 21 is a front partial view of the altered waist play caller of the second embodiment when worn.
 Broken lines in any of the foregoing Figures illustrate environmental structure of the waist play caller and form no part of the claimed design.
